G. T. VAN HORN,

DOOR OPERATOR,

APPLICATION FILED JAN. 9, 1922.

Patented Nov. 21, 1922.

2 SHEETS—SHEET 2.

UNITED STATES PATENT OFFICE.

GEORGE T. VAN HORN, OF NUTLEY, NEW JERSEY.

DOOR OPERATOR.

Application filed January 9, 1922. Serial No. 527,982.

To all whom it may concern:

Be it known that I, GEORGE T. VAN HORN, a citizen of the United States, residing at Nutley, in the county of Essex and State of New Jersey, have invented a new and useful Door Operator, of which the following is a specification.

This invention relates to closure operators, and aims to improve the construction 10 as shown in my Patent Number 1,388,533, and which was granted to me under date of August 23, 1921.

The primary object of the invention is to provide novel means designed for opening 15 garage doors or the like, means including a structure operable from a point remote from the closure, eliminating the necessity of a person alighting from his car to accomplish the opening of the closure.

20 Another object of the invention is to provide means for holding the closures against movement or rattling while in their closed positions, the means being also capable of cushioning the movement of the closures 25 as the same engage their frames.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed, without departing from the spirit of the invention.

Referring to the drawings:

Figure 1 is a fragmental rear elevational view of closures disclosing the same in their 40 closed positions.

Figure 2 is a sectional view through the latch mechanism disclosing the position of the same when the closures are in their open positions.

45 Figure 3 is a sectional view through one of the plungers and its housing.

Figure 4 is a longitudinal sectional view through one of the connecting arms disclosing the adjustable construction.

50 Referring to the drawings in detail, the reference character 5 designates the frame in which the hinged closures 6 and 7 operate. A bracket 8 is supported by the frame, and embodies a pair of arms 9 that are 55 provided with openings to accommodate the vertical shaft 10 that supports the head 11.

This head 11 is formed with an extension 12 that provides a seat for one extremity of the coiled spring 13, the spring being shown as having one end thereof seated in 60 the opening 14 formed in the head 11. The opposite end of the coiled spring has connection with a rotatable adjusting head 15 which is provided with teeth formed in 65 the lower surface thereof, which teeth co-operate with the teeth formed in one of the arms 9 of the bracket 8. Thus it will be seen that the tension of the spring 13 may be regulated by rotating the head 15, it being understood that the tension of the 70 spring forces the teeth into engagement with each other to prevent rotary movement of the head with respect to the arm 9 associated therewith.

A connecting arm indicated at 16 has 75 one end thereof threaded and positioned in a threaded opening of the head 11, as clearly shown by Figure 4 of the drawings, there being provided an opening adjacent the outer end of the arm to accommodate 80 the cotter pin 17, which connects the opposed sections of the arm. A tubular member 18 houses the arm 16 and is provided with spaced openings 19 which may be brought into registry with the opening in 85 the arm 16 to accommodate the cotter pin and hold the tubular member in various positions of adjustment with respect to the arm 16 to lengthen or shorten the throw 90 of the arm. As shown, the tubular section 90 is provided with a threaded portion to accommodate the head 20 which is formed with a keeper 21 to cooperate with a latch member 22 that moves vertically within its housing 23. The housing 23 is formed with 95 lateral elongated openings designed to accommodate the transversely extending pin 24, whereby movement of the latch member 22 within its housing is restricted.

Forming a part of the latch member 22 100 is a rod 25 that extends through an opening in one end of the housing and connects with a suitable flexible connecting member 26 that has connection with the bell crank lever 27, whereby movement of the bell crank 105 lever, results in a relative movement of the latch member 22, it being understood that the latch member is moved against the tension of the coiled spring 28 that is positioned in the housing 23 and embraces portions of 110 the rod 25.

The head 20 is also provided with a cut out

portion formed under the keeper 21 to receive the extension 30 forming a part of the plunger 31, which plunger is mounted in the housing 32 and operates against the tension 5 of the coiled spring 33.

- A cut away portion indicated at 34 is also formed in the head and accommodates the inner ends of the arms 35 and 36, a bolt 37 being provided to connect the arms 35 and 10 36 to the head. The arms 35 and 36 have connection with the closures 6 and 7 respectively, so that movement of the arms caused by the moving of the head 11, results in a relative movement of the closures 6 and 7. 15 Supported by the frame is a latch member 38 which cooperates with a keeper 39 carried by the closure 7, the latch member being designed to engage within the keeper to hold the closures in their closed positions. 20 A flexible member 39' has connection with the latch member and connects with the bell crank lever 40 which in turn is connected with the bell crank lever 41 through the medium of the rod 42, there being provided 25 an operating rod 43 for imparting motion to the latch member 38 through the bell crank levers and rod.

Bell crank lever 27 is connected to the bell crank lever 40 as by means of the rod 30 44, the bell crank lever 40 being also moved by the rod 45 which is connected to the bell crank lever 40 as by means of the rod 46 and bell crank lever 47, the operating member 48 being connected with the bell crank 35 lever 49 for imparting movement to the rod 45 and associated elements.

In order that the latch members will be held in their normal positions, a coiled spring 50 is provided, which coiled spring 40 has connection with one of the bell crank levers as clearly shown by Figure 1 of the drawings, and has one end thereof anchored to the bracket 51, which is secured to the plate 52 on which the latch members are 45 supported, and which is in turn mounted on the closure frame adjacent to the upper portion thereof.

In the operation of the device, it will be seen that when the latch member 38 is op-

erated as by moving the rod 43, the coiled 50 spring 13 being under tension, moves to swing the closures to open positions.

When the closures move to the limits of their open positions, the keeper 21 moves under the latch member 22 where the doors 55 are held in their open positions, eliminating any possibility of the wind blowing the same closed.

It might be further stated that as the keeper 21 moves to its locking position, the 60 member 30 contacts with the head to restrict movement thereof and lock the closures against movement.

Having thus described the invention, what is claimed as new is:

1. A door operator including in combination with a door frame, latch members supported by the door frame, pivoted closures hingedly supported within the frame, a spring controlled arm carrying a head supported by the frame, arms connecting the head to the closures, a keeper carried by the head and adapted to cooperate with one of the latch members for holding the closures in open positions, and means carried by one of the closures and cooperating with the other latch member for holding the closures in their closed positions.

2. A door operator including in combination with a door frame, latch members carried by the frame, hinged closures supported within the frame, a spring controlled arm carrying a head at one end thereof, said head having a keeper and having a cut out portion formed under the keeper, a plunger supported by the frame and adapted to move into the opening of the head when the head is moved into engagement with its latch member, and means for engaging with one of the latch members for holding the closures in their closed positions.

In testimony that I claim the foregoing as my own, I have hereto affixed my signature in the presence of two witnesses.

GEORGE T. VAN HORN.

Witnesses:

A. L. HUNTLEY,
DAVID HALLIDY.
